Primary Examiner — Eric L Goodman*Assistant Examiner* — Lilyana Bekic(57) **CLAIM**

The ornamental design for an inhaler, substantially as shown and described.

DESCRIPTION

FIG. 1 is a top front perspective view depicting an inhaler of our design;

FIG. 2 is a front elevational view of the inhaler of FIG. 1; FIG. 3 is a rear elevational view of the inhaler of FIG. 1; FIG. 4 is a left side elevational view of the inhaler of FIG. 1, the right side elevational view being a mirror image thereof;

FIG. 5 is a top plan view elevational view of the inhaler of FIG. 1; and,

FIG. 6 is a bottom plan elevational view of the inhaler of FIG. 1.

The broken lines in the drawings illustrate portions of the inhaler that form no part of the claimed design.
